UNITED STATES PATENT OFFICE.

RAYMOND ST. CLAIR FOW, OF PHILADELPHIA, PENNSYLVANIA, ASSIGNOR TO FRANK X. MATHIS, OF PHILADELPHIA, PENNSYLVANIA.

Slicing-Machine.

1,208,765.

Specification of Letters Patent. Patented Dec. 19, 1916.

Application filed April 10, 1913. Serial No. 760,179.

To all whom it may concern:

Be it known that I, RAYMOND ST. CLAIR Fow, a citizen of the United States, residing at Philadelphia, in the county of Philadelphia and State of Pennsylvania, have invented certain new and useful Improvements in Slicing-Machines, of which the following is a specification.

Regulating completely the movement of the carriage carrying the material to be sliced so that when required, its rigidity is increased or diminished, making the rind slicing operation positive; making the rind slicing device easily adjustable, so that it can readily be put into and out of operation as desired, and making the cutting movement of the slicing knife very regular and powerful and the carriage movement very steady through the construction and mutual relations of the fly wheel, the apparatus for moving the carriage, and the knife revolving mechanism are features of my invention. Other features will appear from the detailed description.

Figure 1 is a side elevation of my invented device. Fig. 2 is a plan view of the carriage; Fig. 3 is a rear end elevation; Fig. 4 is a section on line X—X on Fig. 1. Fig. 5 is a section on line Y—Y of Fig. 4. Fig. 6 is a rear end elevation of a portion of the carriage showing the feed regulating mechanism. Fig. 7 is a front end elevation of part of the carriage showing the spacing mechanism. Fig. 8 shows the knife and its movable guard looking toward the same from the front end of the machine.

The knife 72, the fly wheel 24 and the carriage 43 are operated from the shaft 31. This shaft is turned by the crank 601 and handle 610. The bevel wheel 29 turns the fly wheel 24 by the bevel wheel 25, and the bevel wheel 30 engaging with the bevel wheel 28, turns, through the shaft 32, the arm 13, that engages in the cam slot 20 in the cam 14 secured to the carriage 43. The shaft 30 also carries the bevel wheel 98, that engages with the bevel wheel 96 on the shaft 90 which carries the sprocket wheel 73, which by the chain 64 turns the sprocket wheel 63 which turns the shaft 60 on which is mounted the knife 72. This construction gives a very rapid rotation to the fly wheel and to the knife. The momentum of the former will prevent the regularity of the movement of the latter from being interrupted by an

occasional hardness of the material to be cut, and the great rapidity of the movement of the knife will enable it to cut through bone or other hard material with ease.

The carriage 43 runs on tracks attached to the framework 110 of the machine. To give the greatest ease to its movement, these tracks should be round rods 11 engaged by lugs 12 on the carriage, projecting below its bed, and fitting the rods. The carriage reciprocating mechanism is as follows. The cam 14 in which is the cam slot 20, is secured to the carriage 43. The pin 15 in the rotating arm 13, engages in the slot 20, and the slot and the arm are so arranged that when the carriage 43 is nearing the end of its movement, the movement of the pin will gradually have become one along the slot 20 with a very slight moving of the carriage, and at the extremity of the carriages' movement, the angular movement of arm 13 will produce, for a moment, a motion of the pin along the slot 20 without producing any forward or backward movement of the carriage 43. The cam slot can be arranged relatively to the axis of rotation of arm 13, and shaped so that the reciprocating movement of the carriage can be hastened or retarded during portions of the reciprocating movement. The cam slot, as illustrated, will cause the rapid withdrawal of the carriage immediately after the cut of the knife is concluded, and will slow up the carriage while the feed regulating mechanism is being operated; this motion is produced by the forwardly bent part 210, of the cam slot 20.

The platform 42 rests on the carriage 43, and moves freely thereon, and can be lifted freely from it. The feed regulating mechanism is as follows: The carriage is provided with the shaft 4 and the worm 1, which engages with the thread 49 of the rack 4' depending from the platform 42, and is rotated by the pawl and ratchet operated gear wheel mechanism which latter is operated by a trip 8, which last is operated by an adjustable stop mechanism. These mechanisms are preferably as follows: The gear wheel 5 is placed on the end of the shaft 4. It meshes with gear wheel 6 concentric with which is the ratchet wheel 7. The trip 8 is mounted concentrically with these wheels and carries the pawl 9. The trip 8 is bent forward at its lower end. The adjustable stop 3 is mounted on the lever 87 fulcrumed on pin 110

88, on the frame 110 of the machine, and is lifted and lowered by moving the head 82 along the scale 81. This head is connected to the lever 87 by the bell crank arm 80. The 5 gear wheels are mounted on the ledge 411 attached to carriage 43 and projecting over frame 110. The trip 5 contacting with the stop 3, in the course of the backward movement of the carriage, causes the last named 10 mechanisms to operate the feed regulating mechanisms.

The material to be spliced is held on the platform 42 by a yielding holder consisting of arms 40 secured rigidly to each other and 15 having branches 45 provided with spurs. These arms are pivotally attached to standards 46 on the platform 42 by the spindle 41 and are yieldingly actuated toward the platform by the springs 74. These springs are 20 attached to the arms 40 and to the block 79 on the spindle 41. The block 79 can be secured after it has been turned in any position to give any desired tension to spring 74. 25 78 is a key to turn the spindle 41. The roller 55 is mounted between the arms of the standard 56. It can be set by the set screw 57, turning in the lug 58 against the arm 59 that, when not held by screw 57 is movable in a hole in lug 58.

30 The holder, the platform, and the material held thereon form a separable portion of the machine freely removable from the carriage, and duplicates of this separable portion may be provided. The fly wheel 24 rests upon roller bearings 26, and is 35 geared to rotate much more rapidly than the arm 13. It revolves on the spindle 32, which turns the arm 13 carrying the pin 15. This spindle also revolves in the same direction 40 as the fly wheel 24, but more slowly. This construction minimizes the friction of the fly wheel. The fly wheel has a very heavy rim and preferably is cast in one piece with the bevel wheel 25. It is contained 45 with very little waste space in the frame 110 that protects the garments of the operator from it.

The rind slicing device is a rotating knife 17 and mechanism for rotating it from the 50 reciprocating movement of the carriage consisting of a spindle 19 on which is placed a gear wheel 18, which is adapted to mesh with the rack 180 placed upon the carriage, when the rod 16, upon which the spindle 19 55 is angularly mounted, is turned. This rod is supported by hangers 36, and may be turned by a head 190. The edge of the knife turns more rapidly than the carriage moves thus securing a very clean cut of the rind, and hence permitting it to be cut very 60 thin and with trifling waste.

The guard of the knife has a permanent and a movable part. The permanent part 70 protects the user of the machine against 65 the part of the knife lying on the opposite

side of the standard 100 from the carriage. The movable part 71 can be drawn down to protect the edge adjacent to the carriage when the machine is not in use. The two parts telescope one inside the other and the 70 inner is held in position partly by the bending in of the inner edges of the outer part. The permanent piece is also supported by the link 69 and the movable by the movable link 67, which has a center of rotation concentric with the shaft 60 and is provided for convenience with the handle 68.

The machine is operated by turning shaft 31 which puts in motion simultaneously all the operative parts of the machine. The 80 construction of the fly wheel and its operative parts enables it quickly to attain great speed so that its momentum will thoroughly regularize the action of the machine. When the rind cutter is to be used, rack 180 and the 85 wheel 18 are brought into connection with each other. The platform can be removed and replaced by a duplicate whenever another material is to be cut. The platform can also be lifted back and set when a fresh 90 piece of material is inserted.

I claim:

1. In a slicing machine, the combination of a rotary knife rotating upon a fixed axis, a carriage, a carriage reciprocating mechanism, and a fly wheel revolving on the shaft of the carriage reciprocating mechanism, and at a more rapid speed than this shaft, all said parts being positively geared together. 95

2. In a slicing machine the combination of the meat slicing knife, the meat carriage, the mechanism for reciprocating the meat carriage, a rotating rind slicing knife, a spindle carrying this knife, a rotatable spindle to which the spindle carrying the knife is attached, running substantially parallel with the meat slicing knife and mechanism for rotating the rind slicing knife when the latter is turned into cutting position. 105

3. In a slicing machine, the combination of the meat slicing knife, the meat carriage, the mechanism for reciprocating the meat carriage, a rotatable rind slicing knife, a spindle carrying this knife, a rotatable spindle to which the spindle carrying the rind slicing knife is attached, running substantially parallel with the meat slicing knife, a rack upon the carriage and a pinion mounted the spindle carrying the rind slicing knife 115 and meshing with said rack.

4. In a slicing machine, the combination of the meat slicing knife, the meat carriage, mechanism for reciprocating the meat carriage, a spindle substantially parallel with the meat slicing knife, a rind slicing knife, a spindle extending angularly from the spindle running substantially parallel with the meat slicing knife and carrying the rind slicing knife, and rack and pinion mecha- 125

nism connecting the carriage and the rind slicing knife and rotating the rind slicing knife at a greater circumferential speed than the speed of the translation movement of the carriage.

5. The combination in a slicing machine having a rotating main shaft, of a rotating knife, a reciprocating carriage, mechanism for reciprocating the carriage toward and 10 away from the knife, said mechanism comprising a finger positively moved through the revolution of the shaft, in a circular orbit, and a cam attached to the carriage and traversed by the finger, a carrying plate for 15 the material to be sliced, mounted on the carriage, step-by-step mechanism for advancing the plate upon the carriage, means for actuating the step-by-step mechanism when the carriage is at a point toward the 20 end of its movement away from the knife, the actuating surface of the cam traversed by the finger during the actuation of the step-by-step mechanism, being, while so traversed by the finger, inclined toward the axis 25 of the orbit in which the finger moves.
6. In a slicing machine, the combination of a main driving shaft, a rotary knife rotating upon a fixed axis and driven from said shaft, a carriage, a carriage reciprocating 30 mechanism comprising a shaft, a fly wheel on the shaft of the carriage reciprocating mechanism, said last-mentioned shaft being driven from the main driving shaft and means for revolving the fly wheel in the 35 same direction as and at a more rapid speed than the shaft of the carriage reciprocating mechanism, the rotary knife, the carriage reciprocating mechanism and the fly wheel being positively geared together.
- 40 7. In a meat slicing machine, the combination of the slicing knife, placed above the

meat table, the chain wheels and chain for the same, a main driving shaft a shaft running at an angle with the main shaft and carrying one of the chain wheels, a bevel 45 gearing connecting the main shaft with the shaft carrying the chain wheel, a meat carriage operating mechanism having a shaft geared directly to the main shaft and a fly wheel geared directly to the main shaft and 50 surrounding and turning in the same direction with but more rapidly than the shaft of the carriage operating mechanism.

8. In a meat slicing machine, the combination with the frame of the main shaft running lengthwise of the frame, a knife positively geared to the main shaft, a crank-handle at the end of the main shaft away from the knife, a carriage, carriage reciprocating mechanism, a perpendicular shaft 55 operatively and positively connected to the carriage reciprocating mechanism and a fly wheel loosely mounted and turning upon the perpendicular shaft in the same direction and faster than the shaft, and positively and 60 operatively geared to the main shaft.

9. In a meat slicing machine, a carriage having a rack on the side thereof, a rind cutter mounted on a spindle, said spindle being turnable about an axis whereby it brings the 70 rind cutter into and out of cutting position, and a gear wheel of less diameter than the diameter of the cutter engaging with the carriage and secured to the spindle between the rind cutter and the said axis of the spindle. 75

In testimony whereof I affix my signature in presence of two witnesses.
